UNITED STATES PATENT OFFICE.

NATHANIEL PLYMPTON, OF NEW YORK, N. Y.

DESIGN FOR A FAN.

SPECIFICATION forming part of Design No. 15,878, dated February 24 1885.

Application filed January 16, 1885. Term of patent 3½ years.

To all whom it may concern:

Be it known that I, NATHANIEL PLYMPTON, of New York, in the county of New York, of the State of New York, have invented and produced a new and original Design for a Fan, of which the following is a specification, reference being had to the accompanying drawing, which exhibits it.

The leading features of the design consist in a cloud, *a*, with a flash, *b*, of lightning proceeding therefrom, a frog, *c*, struck from a stick, *d*, of bamboo, by such flash or ball therefrom, another stick of bamboo leaning against the first one, a quantity, *e*, of shrub-

bery at the bases of such sticks, and finally the figure, *f*, of the full moon as rising in rear of the last stick.

I claim—

The design for a fan, substantially as shown, the same consisting in the representation of the cloud, the lightning-flash therefrom, the frog struck thereby, the bamboo sticks, the shrubbery, and full moon, arranged in manner and on a flat annulus, as set forth.

NATHL. PLYMPTON.
